METHOD OF CONSTRUCTING DAMS

Filed Sept. 7, 1929

FIG. 5

INVENTOR

Fred A. Noetzli

UNITED STATES PATENT OFFICE

FRED A. NOETZLI, OF LOS ANGELES, CALIFORNIA

METHOD OF CONSTRUCTING DAMS

Application filed September 7, 1929. Serial No. 390,870.

This invention relates to improvements in dams and the method of constructing the same.

In large concrete structures many stresses are set up in the structure for various reasons, such as those due to shrinkage of the concrete and temperature changes. Unless these stresses are taken care of at intervals along the concrete structure, cracks develop which are irregular and weaken the structure. This feature has been recognized in my co-pending applications, Serial No. 220,197, filed September 17, 1927, and Serial No. 319,205, filed November 14, 1928, over which the construction disclosed in this application may be considered as an improvement by the reduction or elimination of dangerous stresses through improved construction methods and otherwise as described hereafter.

An object of the invention is to provide a dam and a method of construction for dams of the gravity type whereby joints are established at intervals to permit shrinkage of the concrete and temperature changes without weakening the dam.

Another object of the invention is to provide a method of gravity type dam construction whereby the effect of shrinkage of the concrete is rendered less harmful by constructing certain portions of the dam in the shape of forwardly inclined columns and leaving joints of weakened bond between each two adjacent columns.

Another object of the invention is to provide a method whereby dams of the gravity type may be built safely and economically first to an initial height, and subsequently raised to a greater height, and providing a joint between the old and the later construction in a certain chosen direction, whereby the strength of the structure is not impaired appreciably.

Other objects of the invention are to provide novel and advantageous joint constructions and drainage systems.

With the foregoing and other objects in view which will be made manifest in the following detailed description and specifically

pointed out in the appended claims, refer-

ence is had to the accompanying drawings for an illustrative embodiment of the invention, wherein:

Figure 1 is a schematic elevation of the dam embodying the invention.

Figure 2 is a vertical section through the dam shown in Figure 1 and may be considered as having been taken upon the line 2—2 of Figure 1.

Figure 3 is a vertical section along the line 3—3 through the dam shown in Figure 1.

Figure 4 is a vertical section along the line 4—4 through the dam shown in Figure 1.

Figure 5 is a partial horizontal section along the line 5—5 through the dam shown in Figure 1.

Referring to the accompanying drawings wherein similar reference characters designate similar parts throughout, the dam shown in Figure 1 consists of a wall 1 of concrete designed to withstand water pressure by virtue of its weight, usually called a gravity type dam. The wall may be straight or curved in plan.

Figure 2 illustrates how such a gravity type dam appears in section with the rear side of the wall sloping upwardly and forwardly from the base upwards so that the bottom of the wall is much thicker than the top.

The wall 1 is divided by vertical radial transverse joints 2 into a number of vertical units or slices 3, usually from 40 to 60 ft. thick measured along the axis of the dam. Past experience in concrete dam constructions has shown the necessity of providing such transverse contraction joints 2 in order to prevent vertical cracks in the dam due to the shrinkage of the concrete. This shrinkage, of course, affects the concrete in a similar manner in an upstream and downstream direction. In fact, there is evidence in several existing gravity dams that irregular cracks have occurred across the vertical slices 3 of such dams. From a point where the thickness of the dam near the base exceeds materially the value of 50 ft., I provide one or more longitudinal joints 4 in the vertical slices 3, such as shown in Figures 3, 4, and 5. These joints extend upwardly and forward-

ly from the base of the dam to points near the forward face of the dam. They are arranged at suitable intervals such as to provide means for the concrete to shrink without producing cracks.

The transverse joints 2 and the longitudinal joints 4 may be established in any suitable manner so that there will be weakened bonds arranged along predetermined planes thus tending to form portions or columns 5. The longitudinal joints 4 extend substantially parallel to the direction of the first principal stresses when the dam is fully loaded. In these planes the shear is zero. For safety against undue relative movements between adjacent columns 5 there are provided key and groove connections in the joints 4 which will permit of small movements, for instance, due to shrinkage of the concrete, but will prevent large movements which might endanger the safety of the dam.

In order to accomplish some of the objects of my invention, I pour in the dam series of blocks of concrete in a vertical slice 3, designated in Figure 3 by the reference characters 6, 7, and 8. Block 6 extends between two transverse joints 2 from the upstream face of the dam part way towards the downstream face. Block 7 extends from block 6 an additional distance downstream. Block 8 extends from block 7 to the downstream face. While I have shown in Figure 3 three blocks, 6, 7, and 8, it should be understood that instead of three blocks, only two, or, in case of very thick dams, 4 or more series of blocks may be built in the manner described. The important condition is that the rear face of block 6 and the front face of block 7, also the rear face of block 7 and the front face of block 8, are substantially parallel to the direction of certain principal stresses in the dam when loaded to the crest.

It has been shown by theoretical deductions that in the body of a gravity dam under full load there exist two so-called principal stresses, the direction of the first of which is asymptotic to the direction of the downstream face of the dam and normal to the upstream face. The second principal stresses act perpendicularly to the direction of the first principal stresses. In the directions of the two principal stresses the shear is zero. An inclined joint parallel to the direction of the first principal stress in a gravity dam does therefore not change to any material extent the stress distribution in the dam as a whole.

In constructing the improved dam, I may pour, for instance, block 6 first and give its downstream face a slope substantially parallel to the direction of the first principal stresses at that locality in the dam. Then I establish an area of weakened bond, for instance, by painting the downstream face with a suitable substance, like oil, asphalt, etc., so

as to decrease bonding of the concrete to the face. Then I pour block 7 and treat its downstream face similarly as described for block 6. Then I pour block 8 against the downstream face of block 7.

I may provide key and groove connections between the blocks 6 and 7, also between blocks 7 and 8, or I may stagger the blocks as indicated in Figure 3 whereby some kind of key and groove connections are produced between subsequent layers of concrete.

I may provide drain holes or other suitable means for disposing of water which might tend to accumulate in the areas of contact between the blocks 6 and 7, and 7 and 8, respectively.

In order to provide a proper transmission of stresses in the dam, I pour the blocks on slopes increasing upwardly in a downstream direction, as shown in Figure 3. In this manner the daily construction joints, which are planes of weakness, are more nearly perpendicular to the direction of the first principal stresses in the dam under full load.

In constructing the improved dam, I may pour a series of blocks 6 one on top of the other ahead of the blocks 7 and 8, and in such a manner that the downstream faces of the blocks 6 are substantially parallel to the direction of the first principal stresses in the dam. Subsequently, I pour a series of blocks 7 against the downstream face of the blocks 6, and again make the downstream faces of the blocks 7 extend substantially parallel to the direction of the first principal stresses at those points.

I may also choose to pour a series of blocks 8 first, then a series of blocks 6, and wedge a series of blocks 7 between the blocks 6 and 8. Such a series of blocks 8 or blocks 7, respectively, may be considered as forming upwardly and forwardly inclined columns 5, the upstream and downstream faces of which, are substantially parallel to the direction of the principal stresses in the monolithic dam under full load.

When it is desired to build the improved gravity dam first to an initial height and raise it subsequently to its ultimate height, I build first the upstream portion 9 of the dam as shown in Fig. 4, with a slope of the downstream face of this portion that is substantially parallel to the direction of the first principal stresses in the ultimate dam. When the dam is to be raised I build an inclined column 5, similarly as shown in Fig. 4, against the upstream portion 9 of the dam. I may provide key and groove connections between the upstream portion 9 and the downstream column 5, or extend reinforcing bars 10 across the area of contact between upstream portion 9 and downstream column 5, as indicated in Fig. 4.

In order to prevent water under pressure entering the joints 4, that is the areas of con-

fact between the blocks 6 and 7, 7 and 8, etc. I build in during construction of the dam drainage channels 11 extending along the keys 12 or at other suitable places. I provide shafts 13 extending substantially along the joints 4. Through these shafts 13 the drainage channels 11 may be inspected from time to time, and cleaned, if necessary.

I claim:

10 1. The method of constructing a concrete dam by first building a certain up-stream portion of the dam to an elevation lower than the final height of the dam, then building a down-stream portion against the down-
15 stream face of said up-stream portion, the area of contact between said up-stream and said down-stream portion being substantially parallel to the direction of certain first principal stresses when the dam is fully loaded, and further constructing drainage channels along at least some of said key and groove connections.

2. The method of constructing a concrete dam as described by claim No. 1, and further providing reinforcing bars extending across the area of contact between the up-stream and the downstream portion of the dam.

3. The method of constructing a concrete dam as described by claim No. 1 and further providing means for facilitating the inspection and cleaning of said drainage channels.

4. The method of constructing a concrete dam, said method consisting of pouring certain portions of the dam as a first series of blocks of concrete, said blocks being arranged one on top of the other and extending part way between the upstream and downstream faces of the dam, one upper block being staggered relative to the next block below, there being constructed an adjoining second series of blocks by pouring concrete against one of the faces of the aforesaid first series of blocks, there being areas of weakened bond between the two adjoining series of blocks, said areas extending longitudinally substantially along lines of zero shear in the dam when fully loaded.

5. The method of constructing a concrete dam, said method comprising the pouring of a plurality of blocks of concrete one on top of the other, said blocks extending part way between upstream and downstream face of the dam, the front and rear faces of said blocks extending substantially parallel to certain first principal stresses in the fully loaded dam, the tops and bottoms of at least some of said blocks sloping upwardly in a downstream direction.

60 6. The method of constructing a concrete dam designed to resist water pressure by virtue of its weight, said method consisting of pouring transversely spaced columns each extending upwardly and part way between the upstream and the downstream face of

the dam, the top of at least some of said columns sloping upwardly in a downstream direction allowing the columns to set and shrink, then providing the upstream face of certain of said columns and the downstream face of certain other of said columns with a substance tending to prevent bonding of the concrete, and then pouring the intervening columns, at least certain portions of said faces extending substantially parallel to the direction of zero shear stresses in the fully loaded dam.

7. The method of constructing a concrete dam designed to resist water pressure by virtue of its weight, said method comprising the pouring of a first series of blocks of concrete one on top of the other and extending part way between the upstream and the downstream face of the dam, the tops and bottoms of at least some of said blocks sloping upwardly in a downstream direction, permitting said first series of blocks to set and shrink, and subsequently pouring a second series of transversely disposed blocks against said first series and establishing an area of weakened bond between said two series of blocks, at least certain portions of said area extending substantially parallel to lines of zero shear stresses in the fully loaded dam.

8. The method of constructing a concrete dam comprising a unit defined by transverse contraction joints, said unit being divided by at least one longitudinal contraction joint into portions, said method consisting of alternately raising said portions by the pouring of layers of concrete, establishing a longitudinal contraction joint between two adjoining portions and providing means in said joint for improving monolithic action of said unit, the top of at least some of said layers sloping upwardly in a down-stream direction.

9. The method of constructing a concrete dam comprising units defined by transverse contraction joints, said units being divided by longitudinal contraction joints into portions, said method consisting of pouring blocks of concrete in transversely spaced portions, permitting said blocks to set and shrink, then pouring blocks of concrete in the intervening portion after the initial shrinkage of the first portions has taken place, the top of at least some of said blocks sloping upwardly in a down-stream direction.
